UNITED STATES PATENT OFFICE.

BENJAMIN KOHLMER AND EARL C. KOHLMER, OF MANITOWOC, WISCONSIN.

VEHICLE RADIATOR HEATER.

Application filed April 19, 1926. Serial No. 102,972.

This invention relates to a vehicle radiator heater.

In driving automobiles during cold weather, it is the usual practice to cover the radiator and to thus prevent excessive cooling. However, it is a well known fact that the covers usually become loosened or otherwise give trouble, and are more or less unsightly.

10 This invention is designed to overcome the defects noted above, and objects of this invention are to provide a heater for the radiator which may be instantly thrown into operation by the simple manipulation of a 15 rod or lever or as quickly cut out, and which will insure the proper heating of the radiator in the coldest weather without the use of a blanket or covering shield for the radiator.

20 An embodiment of the invention is shown in the accompanying drawings, in which:

Figure 1 is a diagrammatic view partly in section illustrating the device in its relation to the exhaust manifold and radiator, such 25 view showing the cover of the box removed.

Figure 2 is an enlarged transverse sectional view of the device.

Figure 3 is a view from the rear of the attachment.

30 Referring to the drawings, it will be seen that the usual radiator 1 has been illustrated as well as the exhaust manifold 2. This exhaust manifold normally discharges through the exhaust pipe 3 to the muffler 4, and from 35 thence to the rear of the machine. A valve 4 is interposed between the exhaust manifold and the exhaust pipe 3, and such valve is provided with a flap or valve proper 5 which may be rocked to either of two extreme posi-

40 tions, or may assume an intermediate position. This flap is carried in any suitable manner as by means of the rocking shaft 6 to which an external lever 7 is attached. This lever is operated through the medium of a 45 control rod 8 which passes to any point easily accessible to the driver. The valve 4 has a

forwardly extending opening which receives the forwardly extending pipe 9. This pipe leads to the front of the machine and has its 50 flange 10 attached to the bottom of a box 11 secured to the front of the radiator. Preferably, the box is provided with a pair of side ears 12 which are bolted to the ears 13 of the radiator as shown in Figure 1. It is

provided with a back 14 having a plurality 55 of apertures 15 therein, and is provided with a cover or front 16 as shown in Figure 2.

Within the box, a pipe 17 is positioned and has its flange secured to the bottom of the box. The pipe 17 communicates through an 60 aperture in the bottom of the box with the pipe 9 as shown in Figure 1. The pipe 17 may be of a smaller size than the pipe 9 if desired. It is coiled into one or more loops 65 within the box 11 and discharges into a muffler 18 carried within such box. From the muffler, the products of combustion pass outwardly through the discharge pipe 19 extending downwardly from the box.

Under normal conditions, when average 70 temperature exists, the products of combustion will be discharged from the exhaust manifold through the exhaust pipe 3 by properly setting the valve. However, during cold weather, all or a part of the products of combustion will be passed through the pipe 9 to the pipe 17. This pipe 17 will heat the interior of the box 11 and the heat 75 will not be communicated to the radiator.

It is to be noted that the heat is imparted 80 to the lowest portion of the radiator which is the coldest portion thereof, and consequently, by properly adjusting the valve, it is an easy matter to maintain the ideal temperature for 85 perfect operation.

It will be seen that an extremely simple device has been provided of novel construction, which will maintain the temperature of the circulating water at the ideal temperature 90 irrespective of weather conditions, thus permitting free driving of the car without a blanket or shield even in the most severe 95 weather.

Although the invention has been described in considerable detail, such description is 95 intended as illustrative rather than limiting as the invention may be variously embodied and as the scope of such invention is to be determined as claimed.

We claim:

1. In an automobile, the combination of 100 an exhaust manifold, a radiator, a heater for said radiator comprising a box having an apertured rear portion and attached to said radiator, and having a pipe attached to said exhaust manifold and adapted to receive the products of combustion from the exhaust manifold, said pipe being looped 105

through said box, and a muffler carried within said box and discharged downwardly through the bottom of said box.

2. In an automobile, the combination of
5 an exhaust manifold, a rearwardly extending exhaust pipe, a forwardly extending pipe, a valve interposed between said exhaust manifold and said pipes and adapted to direct the products of combustion into
10 either of said pipes, a radiator, a metal box secured to the lower front portion of said radiator and having communication with said radiator through its rear side, said for-

wardly extending pipe passing through said box, a muffler carried within said box and communicating with said forwardly extending pipe, and a discharge pipe leading from said muffler and discharged through the bottom of said box.

In testimony that we claim the foregoing
15 we have hereunto set our hands at Manitowoc, in the county of Manitowoc and State of Wisconsin.

BENJAMIN KOHLMEIER.
EARL C. KOHLMEIER.
